UNITED STATES PATENT OFFICE.

ARTHUR C. KELLE, OF CANTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

MULTIBREAK ELECTRIC SWITCH.

Application filed April 1, 1925. Serial No. 19,988.

This invention relates to electric switches and particularly to that type of electric switch characterized by having means to interrupt the circuit through it at a plurality of points 5 arranged electrically in series.

An object of this invention is the provision of an improved form of movable switch member for the above type of switch and especially characterized by a strong and rigid construction, particularly in the manner of supporting and electrically connecting the arcing members which provide for the plurality of circuit interrupting points in the circuit.

A further object is generally to improve 15 the construction and operation of electric switches.

Certain features of this invention are disclosed in a co-pending application of William S. Edsall, Serial No. 19,990, filed April 1, 20 1925, and assigned to Condit Electrical Manufacturing Company.

Fig. 1 is a side elevation of the stationary and movable switch members of an electric switch embodying the invention.

Fig. 2 is a section along line 2—2 of Fig. 1.

Fig. 3 is a front elevation of the stationary arcing member support.

Fig. 4 is a plan view of the supporting bracket for the insulating support of Fig. 3.

Fig. 5 is a plan view of a movable switch member embodying the invention and especially arranged for two brush or bridging members.

Fig. 6 is a side elevation of Fig. 5.

Fig. 7 is a view similar to Fig. 5 but showing a modified form especially adapted for a single brush or bridging member.

Fig. 8 is a partial sectional elevation of Fig. 7, some of the elements being removed.

Fig. 9 is a perspective detail of a supporting bracket for a stationary arcing member.

Fig. 10 is a diagrammatic representation of the current path through the switch subsequent to the opening of the main contacts.

As shown in Figs. 1 and 2, the switch here shown as embodying the invention includes the two stationary switch members including the insulated studs 10 and 12 to the lower ends of which are secured contact blocks 14 and 15.

The lower faces of said blocks are adapted to be engaged directly by brush or bridging members forming a part of the movable switch member.

The switch here shown is arranged to pro-

vide four points for circuit interruption 55 which are disposed electrically in series between the stationary switch members whereby four circuit interrupting arcs may be drawn. To this end the stationary switch members are provided with stationary arcing 60 members 18 and 20, which arcing members are more or less elongated and wedge shaped at their lower ends. Said stationary arcing members are disposed on similar sides of the stationary switch members and in spaced 65 relation therewith and away from each other. Said stationary arcing members are supported in the aforesaid relation by and are electrically connected with said stationary switch members by means of supporting brackets 22, 70 a perspective view of one of which is illustrated in Fig. 9. Said supporting brackets are attached removably to the contact blocks by suitable means as bolts 24 and are formed with outwardly-divergent and vertically- 75 elongated projections 26 which are received in slots in the upper end of said stationary arcing members. Bolts 28 are passed through said projections 26 and the upper ends of said stationary arcing members 80 whereby to secure said arcing members detachably to said supporting brackets. Similar stationary arcing members 30 and 32 are similarly disposed on the opposite sides of said stationary switch members and are electrically connected and mechanically supported in spaced relation by a bar 34. Said 85 bar is secured by screws 36 to the supporting bracket 38. Said supporting bracket is fixed to the lower end of a vertical insulating pillar 90 40. An attaching bracket 42 is fixed to the upper end of said pillar by which said pillar is secured rigidly to a support 44; and said bracket is provided with an elongation 46 which is disposed between and insulated from the stationary switch members and is formed with bolt holes 48 through which attaching bolts 50 are passed.

The movable switch member, with which this invention is more particularly concerned, includes one or more brush or bridging members and a plurality of arcing members, which arcing members are adapted to engage and cooperate with the above described stationary arcing members. In the modification illustrated in Figs. 7 and 8, the movable switch member includes a supporting member 52, which member is provided with a semi-cir-

cular, tapered and vertically-extended recess 54 therein in which an insulating switch rod 55 is adapted to be received. A cap 56 is provided with a complementary recess 58 and said cap is adapted to be clamped to the supporting member and switch rod by suitable means as bolts 60. Said supporting member is formed with a base-plate 62 which extends horizontally in opposite directions from the lower part of said supporting member; and a brush or current carrying member 64 is secured removably to the end face of said base plate by a suitable means as the bolts 66. Said supporting member is formed or provided with a pair of oppositely directed and downwardly extended arms 68 and 70, the outer ends of which arms are reflexed forwardly whereby approximately to lie in the vertical plane of the switch rod; and said arms are disposed approximately at right angles to the brush member. Arcing member supports are adapted to be carried by said arms and to this end the lower faces of said arms are formed or provided with semi-circular recesses 72 therein; and cap members 74 having complementary recesses are secured to said arm by the bolts 76.

The movable arcing member supports comprise cylindrical rods 78 and 80 which rods are of a substantial length and diameter and are composed of some suitable insulating material. Said rods are clamped, approximately at mid-length, in and to the ends of said arms 68 and 70 by the cap members 74 and are thereby firmly secured to the supporting member 52. Said rods are formed or provided with reduced and square end-portions 82 on which the arcing members are disposed.

As here shown, each arcing member comprises a pair of juxtaposed contact members 83 and 84 which are adapted to be moved upwardly when the switch is moved into closed position to engage opposite faces of the stationary arcing members. Said contact members are secured to the upper ends of flexible spring members 86 whereby they may yield outwardly in contact with the stationary arcing members. The lower ends of said spring members 86 are fixed to an attaching member 88, the structure of which is more particularly shown in Fig. 8. Each attaching member is formed with a square aperture therein in which the square end-portion 82 of a supporting rod is adapted to be received. A slot 90 is extended from the lower face of the attaching member into the aperture and a clamping bolt 92 is passed through the slotted end of the attaching member whereby to clamp the attaching member firmly to the insulating rod.

The arcing members at the proximate ends of said rods 78 and 80 are adapted to be electrically connected. To this end, the attaching members are formed with approximately parallel projections 94 and a U-shaped and

substantially rigid and electrically conducting bar 96, comprising a brace-member, is detachably secured to proximate projections by suitable means as by bolts 98. Said bars 96 also serve to impart additional rigidity to the structure.

As thus arranged the two contact members on the opposite ends of one insulating rod, as the rod 80, for instance, are adapted to engage with the stationary arcing members carried by the stationary switch members while the other two arcing members are adapted to engage the stationary arcing members carried by the insulating pillar 40 whereby to provide a conducting path between the two stationary switch members which includes all four sets of arcing members in series so that four circuit interrupting arcs may be drawn in series when the switch opens.

The modification illustrated in Figs. 5 and 6 is similar in principle to the construction illustrated in Figs. 7 and 8 except that provision is made for two brush or bridging members 64^a and 64^b. In this modification, said arms 68^a and 70^a are independent of each other and are secured together in alignment and also to the supporting rod by the bolts 60^a. Each arm is provided with a base plate 62^a to which a brush member is secured. The construction is otherwise identical to the previously described modification.

The structure may be otherwise modified without departing from the spirit of the invention.

I claim:

1. A movable switch member for a multi-break electric switch comprising a movable supporting structure having a pair of oppositely-directed arms, an insulating rod carried by each arm and extended transversely thereof and in opposite directions therebeyond, arcing members carried at both ends of said rods, and means carried by said movable structure arranged electrically to connect the arcing members on similar ends of said rods.

2. A movable switch member for a multi-break electric switch comprising a supporting structure having a pair of oppositely-directed arms, an insulating rod carried by each arm and extended transversely thereof and in opposite directions therebeyond, electrically conducting brace-members rigidly connecting the similarly-extended ends of said rods on both sides of said arms, and arcing members disposed at the connections between said rods and brace-members.

3. A movable switch member for a multi-break electric switch comprising a supporting structure having a pair of oppositely-directed arms, an insulating rod carried by each arm and extended transversely thereof and in opposite directions therebeyond, contact supporting members fixed to both ends of each rod, brace-members rigidly connected

to the adjacent ends of said supporting members on both sides of said arms, and arcing members carried by said supporting members.

- 5 4. A movable switch member for a multi-break electric switch comprising a vertically-movable supporting structure having a pair of oppositely-directed arms, an insulating rod carried by each arm and extended transversely thereof and in opposite directions therebeyond, said rods having reduced and squared end-portions, arcing members having square apertures in which said end-portions are received, means to secure said arcing members in the aforesaid relation, and electrical conductors on both sides of said structure connecting the adjacent arcing members of said two rods.
- 10 5. A movable switch member for a multi-break electric switch comprising a supporting structure having a pair of oppositely-directed arms, an insulating rod carried by each arm and extended transversely thereof and in opposite directions therebeyond, said rods having reduced and squared end-portions, arcing members having square apertures in which said end-portions are received, said arcing members having projections disposed in approximate parallelism with said rods, and U-shaped brace-members fixed to the projections of proximate arcing members of said rods.

- 15 6. A movable switch member for a multi-break electric switch comprising a supporting structure having a pair of oppositely-directed arms, a bridging member carried by said structure intermediate and transversely of said arms, an insulating rod carried by the end of each arm and extended in opposite directions therebeyond and disposed in approximate parallelism with said bridging member, and arcing members carried by the ends of said rods.

- 20 7. A movable switch member for a multi-break electric switch comprising a supporting structure having a pair of oppositely-directed arms, a bridging member carried by said structure intermediate and transversely of said arms, an insulating rod carried by the end of each arm and extended in opposite directions therebeyond and disposed in approximate parallelism with said bridging member, arcing members carried by the ends of said rods, and electrical conductors connecting said arcing members.

- 25 8. A movable switch member for a multi-break electric switch comprising a supporting structure having a pair of oppositely-directed arms, a bridging member carried by said structure intermediate and transversely of said arms, an insulating rod carried by the end of each arm and extended in opposite directions therebeyond and disposed in approximate parallelism with said bridging member, arcing members carried

by the ends of said rods, and electrical conductors connecting the arcing members on similar ends of said rods.

9. A movable switch member for a multi-break electric switch comprising a supporting structure having a pair of oppositely-directed arms, a bridging member carried by said structure intermediate and transversely of said arms, an insulating rod carried by the end of each arm and extended in opposite directions therebeyond and disposed in approximate parallelism with said bridging member, arcing members carried by the ends of said rods, and brace-members extended between and fixed rigidly to the proximate ends of said rods, said brace-members also providing electrical connection between said arcing members.

10. A movable switch member for a multi-break electric switch comprising a supporting structure having a pair of oppositely-directed arms, a base-member disposed beneath said arms, a bridging member attached to said base-member and extended transversely and on opposite sides of said arms, an insulating rod carried by and extended transversely and on opposite sides of each arm, arcing members carried by the ends of said rods, and electric conductors connecting the arcing members on similar ends of said rods.

11. A movable switch member for a multi-break electric switch comprising a supporting structure having a pair of oppositely-directed arms, a base-member disposed beneath said arms, a bridging member attached to said base-member and extended transversely and on opposite sides of said arms, an insulating rod carried by and extended transversely and on opposite sides of each arm, arcing members fixed to the ends of said rods, and electrically-conducting brace-members rigidly connecting the arcing members on similar ends of said rods.

12. A movable switch member for a multi-break electric switch comprising a vertically-movable supporting structure having a pair of independent arms, means rigidly connecting said arms to extend in opposite directions, a lifting rod clamped between said arms, an insulating rod carried by the end of each arm and extended transversely and in opposite directions thereof, arcing members carried by the ends of said rods, and means electrically connecting said arcing members in pairs.

13. A movable switch member for a multi-break electric switch comprising a vertically-movable supporting structure having a pair of independent arms, means rigidly connecting said arms to extend in opposite directions, an insulating rod carried by the end of each arm and extended transversely and in opposite directions thereof, arcing members carried by the ends of said rods, means electri-

cally connecting the arcing members of similar ends of said rods, and a brush member carried by said supporting structure between said insulating rods.

14. A movable switch member for a multi-break electric switch comprising a supporting structure having a pair of independent arms, means rigidly connecting said arms to extend in opposite directions, a bridging member carried by each arm and extended trans-

versely and in opposite directions thereof, an insulating rod carried by the end of each arm and extended transversely and in opposite directions thereof, arcing members carried by the ends of said rods, and means electrically connecting said arcing members in pairs. 15

In testimony whereof, I have signed my name to this specification.

ARTHUR C. KELLE.
